E. E. THIEL

PRINTING PLATE HOLDER

Filed August 22, 1924

INVENTOR:
EMIL E. THIEL

BY
Allen & Allen
ATTORNEYS.

UNITED STATES PATENT OFFICE.

EMIL E. THIEL, OF CINCINNATI, OHIO, ASSIGNOR TO THE PRINTING MACHINERY COMPANY, OF CINCINNATI, OHIO, A CORPORATION OF OHIO.

PRINTING-PLATE HOLDER.

Application filed August 22, 1924. Serial No. 733,646.

To all whom it may concern:

Be it known that I, EMIL E. THIEL, a citizen of the United States, and a resident of Cincinnati, in the county of Hamilton and State of Ohio, have invented certain new and useful Improvements in Printing-Plate Holders, of which the following is a full, clear, and exact description, reference being had to the accompanying drawing, 10 forming part of this specification.

My invention relates to devices adapted for use with a bed, for retaining printing plates and the like thereon. It further relates more particularly to such devices where 15 used with printing plate beds having numerous holes therein, into which the devices of my invention are dropped.

"Drop-in hooks" as such devices are termed commercially, usually comprises a 20 jaw, and a holder, the latter being adapted for dropping into the holes or channels in a printing plate bed, and some kind of means resulting in the operator being able to adjust the position of the parts so as to bring 25 the jaw up against a printing plate thereby holding the plate down on the bed, and also holding it against displacement in the plane of the bed.

It is the object of my invention to provide 30 a structure for the indicated purpose which operates without pivot pins, and has a jaw which slides in a line parallel with the surface of the press bed. It is also my object to provide a simple and very effective hold- 35 down device, which retains the carrier element of the structure within a press bed hole, removably, but very firmly, and in an automatic manner, permitting a close fit of the carrier to the press bed hole.

40 I accomplish my objects by that certain construction and arrangement of parts to be hereinafter more specifically pointed out and claimed.

In the drawing:

45 Figure 1 is a top plan view of one of the devices in place in a press bed.

Figure 2 is a perspective of the device.

Figure 3 is another perspective taken on a different angle.

50 Figure 4 is a section on the line 4—4 of Figure 3.

Figure 5 is a section on the line 5—5 of Figure 2.

55 I have illustrated a portion of a press bed 1, having holes 2 therein which are enlarged

at 3 at the lower ends to provide retaining shoulders for the hold-down spring of the carrier. The carrier is formed with a base 4, which has a channel about part of its lower end, in which is set a spring 6, formed 60 in a crescent shape. A piece of thin metal shaped as a cross, as indicated at 7 is set into the channel, at what may be termed the rear of the base, so as to close off the channel, leaving it as a passageway for the spring 65 at this point. The cross-shaped piece is held in place by a tight fit in the vertical grooves 7^a formed in the rear of the barrier base.

The spring is so shaped that when in 70 place in the carrier, its ends tend to spring out as at 6^a, on both sides of the carrier, so that when the carrier is thrust down into the press bed hole the spring ends will automatically spring out and engage under 75 the shoulder at the base of the said hole.

The base is formed with an upper surface forming an inclined plane 8, from which the two upright sides extend upwardly to serve as housings within which the jaw will slide. 80

The channel for the spring is deeper cut into the base where the cross-shaped closure is placed over it, and a hole 8^a is drilled down through the high portion of the inclined plane of the base, into the channel, 85 so that an instrument can be inserted through the hole, and the spring pushed outwardly of the passageway in which it lies, thereby retracting the ends, so that the carrier can be lifted out. 90

The uprights of the carrier are formed with channels 9, 9, for guides for the jaw. The jaw is formed with the usual head 10, and with a slide block 11 engaging in said channels, so that the jaw is held slidably in 95 the carrier with a movement parallel with the bed.

A left hand threaded socket 12 is formed in the slide block, into which extends a 100 hole 13 from the top of the jaw so that the adjusting screw within the socket is available for turning through the top of the jaw. A wedge element 14 is provided, which is adapted to slide on the inclined plane of the base. It fits snugly but slidably between the uprights of the carrier and has a right hand socket 15 for the screw. The screw 16 may have a button head 17 on its lower end to prevent its removal from the wedge during operation of the device, and to keep 110

the wedge and jaw slide block together at all times so that the wedges do not become lost during shipment or storage. The screw also has a square socket 18 in its upper end.

5 In operation the jaw, slide block and wedge are moved into place within the carrier from the side thereof, and the spring ends fitted into a press bed hole, whereupon the device can be thrust down into place.

10 The base and sides of the carrier may fit the hole snugly but slidably, as the spring ends when inserting and removing the device are completely within the confines of the wall of the base of the carrier.

15 In use a tool is inserted through the jaw head, and the screw is turned, which results in the wedge riding down the incline and thereby thrusting the jaw toward the printing plate to be held on the bed, said jaw

20 moving in the plane of the bed. The engagement of the jaw with the plate is very firm, as the slide block may fit the guides in the carrier snugly and the screw, being right and left hand threaded acts very rapidly,

25 and can have a pitch which prevents the jogging loose of tight engagement, while permitting very rapid clamping adjustment. Reverse turning of the screw will release the jaw, whereupon the carrier can be lifted out, by means of pulling the spring ends out of engagement, as has been described.

Having thus described my invention, what I claim as new and desire to secure by Letters Patent, is:—

35 1. In a device of the character described, the combination with a carrier, having a body to fit in an aperture in a press bed, a jaw held movably in the carrier, the carrier having an inclined base and the jaw provided with a wedge for engagement with 40 the inclined base of the carrier, and means for adjusting said wedge and incline engagement to alter the position of the jaw and carrier.

45 2. In a device of the character described, the combination with a carrier having an inclined base, and uprights, a jaw held movably in the uprights, a screw in the jaw, available for operation, and a wedge on the 50 screw and held between the uprights, whereby turning of the screw will force the wedge along the incline, and the relative positions of jaw and carrier will be altered, for the purpose described.

55 3. In a device of the character described, the combination with a carrier having an inclined base and uprights, a jaw having a

bearing block slidably supported in a horizontal plane in the uprights, a wedge for engagement with the incline, and means for 60 adjustably carrying the wedge on the jaw.

4. In a device of the character described, the combination with a carrier having an inclined base and uprights, a jaw having a bearing block slidably supported in a horizontal plane in the uprights, a wedge for engagement with the incline, and means for 65 adjustably carrying the wedge on the jaw, said means comprising a screw engaging in the jaw, and available for turning, said 70 screw being engaged also in the wedge.

5. In a device of the character described, the combination with a carrier having an inclined base and uprights, a jaw having a bearing block slidably supported in a horizontal plane in the uprights, a wedge for engagement with the incline, and means for 75 adjustably carrying the wedge on the jaw, said means comprising a screw engaging in the jaw with a thread in one direction, and 80 available for turning, and a threaded socket in the wedge, said screw having threads formed in the other direction for engaging in said wedge, for the purpose described.

6. In a device of the character described, a carrier having a body to fit an aperture in a press bed, said bed having an enlargement at the under end thereof for forming a hold-down shoulder around the aperture, a spring in the carrier mounted within the confines 90 thereof and exposed for expansion of its ends into engagement with the shoulder, and an aperture through the carrier within which the spring is partly located, said carrier having mounting means for the spring 95 to permit a tool to be inserted through the aperture, for retracting the spring so as to remove said ends from engagement.

7. In a device of the character described, a carrier having a body to fit an aperture in a press bed, said bed having an enlargement at the under end thereof for forming a hold-down shoulder around the aperture, a channel in the carrier, a spring mounted within the channel, and having portions tending to 100 expand so as to engage under said shoulder, means closing the channel, so as to confine the spring intermediate said portions, against expansion, and an aperture through the carrier extending into said confined portion 105 thereof, for insertion of a tool to withdraw the spring portions into the confines of the body of the carrier.

EMIL E. THIEL.
